UNITED STATES PATENT OFFICE.

JOHN CAHILL, OF NORFOLK, VIRGINIA.

ROLLING DOOR OR SHUTTER AND MEANS FOR OPERATING THE SAME.

No. 812,722.

Specification of Letters Patent.

Patented Feb. 13, 1906.

Application filed May 29, 1905. Serial No. 262,825.

To all whom it may concern:

Be it known that I, JOHN CAHILL, a citizen of the United States, residing at Norfolk, in the county of Norfolk and State of Virginia, have invented a new and useful Improvement in Rolling Doors or Shutters and Means for Operating the Same, of which the following is a specification.

My invention relates to improvements in what are known as "rolling" doors or shutters and means for operating them, its main object being to provide a rolling door or shutter which shall be simple in construction and noiseless in operation.

Another object is to close the opening or space at the top of the doorway usually caused by the unwinding of the door or shutter.

Another object is to provide improved means for operating the door or shutter.

With these and other objects in view my invention consists of certain novel features of construction, arrangement, and combination of parts, as will be hereinafter fully described, and pointed out in the claims, reference being had to the accompanying drawings, in which—

Figure 1 is a front elevation, partly in section, of the door-operating mechanism. Fig. 2 is an end view of shaft, showing gear for turning same. Fig. 3 is a sectional end view showing door or curtain rolled up and the equalizing-spring. Fig. 4 is a sectional view of door, showing "wicket" raised. Fig. 5 is a sectional end elevation showing the door closed and the equalizing-spring. Fig. 6 is a detail sectional view of the spiral cam, shaft, and bracket. Fig. 7 is a sectional elevation of the spiral cam and the cone-pulley.

The usual method of constructing wooden rolling doors, shutters, or partitions is by mortising a number of slats and stringing them tightly on metal bands. Another way is to fasten the metal bands to spring-anchors that are fastened to a wide bottom bar, enough tension being put on the anchors to hold the slats tightly together when hung from the top; but this construction is open to the objection that atmospheric changes (particularly when the door or shutter is used as an outdoor appliance) cause swelling of the slats, putting extra tension on the springs, and rendering operation of the door or shutter difficult, besides having to use a very large bottom bar to hold the spring-anchors, said bottom bar necessarily decreasing the size of the

door or shutter opening. To overcome these objections, I have devised the various improvements, which I shall now proceed to describe.

1 represents a door or shutter composed of slats 2, mortised and strung on metal bands 3, which are secured in the bottom bar 4 by the pins or anchors 5. The wooden slats are threaded on the bands until the door or shutter opening is filled. Then an iron slat 6 is put on to keep the wooden slats tightly together. Then enough more wooden slats are put on and another iron slat 6^a to further keep the slats together and the iron slats to balance one another. A reasonable space 7 is then left to allow for atmospheric expansion of the wooden slats between top iron slat and the top bar, so that in wet weather the wooden slats will expand and not cause the extra pull on the bands. When the wooden slats shrink in dry weather, the iron slats will by their weight keep the wooden slats together.

8 represents the wall, to which are secured the brackets 9, which support the shaft 10.

11 represents rollers which fit around the shaft and run on bearings in brackets 9, which are elongated.

12 represents barrels or pulleys fastened by set-screws to the shaft 10. To these barrels or pulleys the top bar 6^b is secured by means of a screw passing through the bands 3, so that the door or shutter can be coiled on said pulleys.

13 is a variable balance or cone-shaped drum having a threaded circumference, said drum being rigidly secured to one end of the shaft 10.

14 is a wire rope secured at one end to the cone-shaped drum and at its other end to a coiled spring 15, housed in a tube or casing 16, rigidly secured at its lower end to the casting 17, which is secured to the floor or a suitable base, said casting 17 having the openings 18 to allow access to a turnbuckle 19, which is attached at its upper end to the lower end of the spring 15 and at its lower end to casting 17. The object of the cone-shaped drum and spring is to keep the power strong enough to raise the door or shutter when the spring is discharging. The casing 16 is secured at its upper end to the bracket 9 by a plate 20.

21 22 are guides for the door or shutter and are secured to the wall by bolts or other suitable means.

22 22 are what I term "spiral cams," secured on both ends of shaft 10, the pitch of

the spiral cam being the same as the coils of the shutter or door when rolled up, the roller 23, mounted on a rigid pin 24, projecting from the face of the brackets, extending into the spiral groove of the cams 22 22. It will be observed that the opening in the brackets is somewhat elongated, forming a track, so that the shaft 10 may move to and from the wall of the building, and the engagement of the roller 23 with the spiral groove causes the back-and-forth movement of said shaft 10, by virtue of which action the uncoiled part of the door or shutter is kept at the same distance from the wall at all points of its operation. In Fig. 6 the position of the cam 22, roller 23, and shaft 10 with respect to the bracket 9 when the door or shutter is one-half opened or raised is shown.

On the extreme right-hand end of shaft 10 is suspended a bracket or hanger 25, substantially square in shape, as shown in Fig. 2. To the shaft 10 at this end is keyed a pinion or gear-wheel 26, which meshes with a smaller pinion or gear-wheel 27, attached to a sprocket-wheel 28, which is mounted on a small shaft 29, secured in the hanger 25. Said hanger is open at the bottom to permit the passage of sprocket-chain 30, which passes over sprocket-wheel 28 to turn shaft 10, and thus operate the door or shutter, the chain being guided by a chain-guard 31.

32 represents rollers mounted on the inner face of the hanger to prevent said hanger from tipping up when the door or shutter is operated.

36 is a wicket-door constructed in the same manner as the main door or shutter and may be hung from its top or side, but preferably from its top, part of the bottom bar 4 of the main door being cut away, the bottom bar 33 of the small door or wicket taking its place. This wicket is rabbeted all around to make a good joint, and 34 is a hasp-bolt, which fastens the wicket-door. The advantage of hanging the wicket-door from its top is that it will close of its own weight, and there will be no danger of its opening and being broken when the main door or shutter is being rolled up.

50 The opening which usually exists in the use of ordinary rolling doors or shutters between the shaft and the wall when unrolled is closed by my device. Ordinarily if the door or shutter has five coils and the slats are one inch thick then the opening would be five inches wide. By the use of the spiral cams of my invention, the spirals of which are of the same pitch as the thickness of the slats during the operation of the shutter or door, said shutter or door is automatically kept the proper distance from the wall and absolutely leaves no opening, as the position of shaft 10 on the brackets is controlled by the spiral cams 22 and the rollers 23. This construction also keeps the coil directly over

the guideways, which greatly reduces friction, and the coils of the door are balanced by the iron slats 6 and 6^a when the door or shutter is rolled up, as indicated in Fig. 3.

The spring 15 is an expansion-spring, and the cone-shaped drum 13 is sufficiently small at one end and varies in diameter as to cause the spring in the present instance to travel at a ratio slightly less than one to two. It will be noted that when the spring 15 is contracted it reaches nearly one-half way up the casing, so that the door or shutter will have to go up or down twice as fast as the spring will contract or expand. The tension of said spring is kept even or uniform by means of the variation of the diameters on the drum 13. As the barrels or pulleys around which the shutter or door coils are about twice the size or diameter of the drum 13, it will be seen that the shutter or door will coil or uncoil twice as fast as the spring will contract or expand.

The top bar or slat 6^b, as has been stated, is secured to the pulleys 12, and, as shown, these pulleys have a portion of their periphery cut out eccentrically, so that the outer face of bar or slat 6^b will be substantially flush with the uncut portion of said pulleys.

As the casing 16 is secured to the floor or ground, it acts as a support and a brace to the bracket 9.

As the coil of the shutter or door when it rolls up is at its largest diameter, I put stronger straps or bands 35 in the wicket-door, so that it will be stiffer than the rest of the shutter or door.

What I claim is—

1. A vertically-disposed flexible door or shutter consisting of a series of horizontal wooden slats and interposed heavy metallic slats loosely threaded on tapes, whereby a tight joint between the slats below the metallic slats will be at all times maintained.

2. A vertically-disposed flexible shutter or door consisting of a series of wooden slats, a heavy metallic slat mounted on top of said wooden slats, a smaller series of wooden slats mounted on top of the aforesaid metallic slat, another heavy metallic slat surmounting the last-mentioned metallic slat, and a top bar, all threaded on tapes, the wooden and metallic slats being loosely threaded thereon and the said top bar and tapes adapted to be secured to a rotary shaft.

3. In a device of the class described, a flexible door or shutter adapted to close an opening in a wall, a shaft to which said door or shutter is secured, supports for said shaft, and means for causing the shaft to move transversely toward the wall as the door or shutter uncoils, and away from the wall as it is coiled.

4. In a device of the class described, a flexible door or shutter adapted to close an opening in a wall, a shaft to which the upper end

of the door or shutter is secured, supports for said shaft, means for causing the shaft to move transversely toward the wall with respect to its supports as the door or shutter is uncoiled, and away from the wall as it is coiled and means attached to one end of the shaft for causing rotation of the same.

5. In a device of the class described, a flexible door or shutter adapted to close an opening in a wall, a shaft to which said door or shutter is secured, supports for said shaft, cams mounted on said shaft adjacent to its supports, and coöperating means on said support for engaging said cams to cause the shaft to move transversely with respect to its supports, away from the wall when the flexible door is coiled and toward the wall as it is uncoiled.

6. In a device of the class described, a flexible door or shutter adapted to close an opening in a wall, a shaft to which said door or shutter is secured, supports for said shaft, spiral cams rigidly secured to said shaft adjacent to its supports, and projections on said supports engaging the spiral cams and coöperating therewith to cause the shaft to move transversely with respect to its supports, away from the wall as the door or shutter is coiled and toward the wall as it is uncoiled.

30 7. In a device of the class described, a flexible door or shutter adapted to close an opening in a wall, a shaft to which said door or shutter is secured, supports for said shaft, a spirally-grooved cone-pulley secured to one end of said shaft, an expansion-spring anchored at one end and a flexible connection between the cone-pulley and the free end of the expansion-spring, the shaft to revolve and move transversely on its supports toward the wall as the door or shutter uncoils, and away from the wall as it is coiled.

8. In a device of the class described, a flexible door or shutter, a shaft to which said door or shutter is secured, supports or brackets for said shaft, a spirally-grooved cone-pulley secured to one end of said shaft, an expansion-spring suitably anchored at one end, a flexible connection between the cone-

pulley and the free end of the expansion-spring, and means for regulating the tension 50 of the spring.

9. In a device of the class described, a flexible door or shutter adapted to close an opening in a wall, a shaft rotatably mounted in suitable supports, drums rigidly secured to 55 said shaft, said door or shutter rigidly secured at its upper end to said drums, and means for causing the shaft to rotate and move transversely on its supports, away from the wall as said door or shutter is coiled 60 and toward the wall as it is uncoiled.

10. In a device of the class described, a flexible door or shutter consisting of a series of slats threaded on tapes, and a top bar secured to the upper ends of the tapes, leaving 65 a space between the main body of the door or shutter and its top bar, a shaft to which said top bar is rigidly secured, supports or brackets for said shaft, said shaft being rotatably mounted in said supports, and adapted to 70 move transversely in said supports when the door or shutter is coiled and uncoiled.

11. In a device of the class described, a flexible door or shutter, a shaft, supports or brackets for said shaft, drums rigidly secured to said shaft, said door or shutter rigidly secured at its upper end to the said drums, spiral-groove cams secured to said shaft adjacent to said supports or brackets, projections on said supports or brackets engaging 80 the spiral-groove cams, a spirally-threaded cone-pulley secured to one end of said shaft, an expansion-spring vertically disposed and suitably anchored at its lower end, a flexible connection secured at one end to the upper 85 end of the expansion-spring and at its other end to the spirally-grooved cone-pulley, and means for rotating said shaft, whereby the said shaft will be caused to rotate and move transversely in its supports or brackets, when 90 the door or shutter is coiled and uncoiled.

JOHN CAHILL.
